(57) **CLAIM**

The ornamental design for an expandable wire bangle bracelet, as shown and described.

DESCRIPTION

FIG. 1 is a perspective view of an expandable bangle bracelet, showing my new design;

FIG. 2 is a top plan view thereof;

FIG. 3 is a bottom view thereof;

FIG. 4 is a left side view thereof;

FIG. 5 is a right side view thereof;

FIG. 6 is a rear view thereof;

FIG. 7 is a front view thereof;

FIG. 8 is a perspective view of a second embodiment of my design; and,

FIG. 9 is a perspective view of a third embodiment of my design.

The subject matter depicted in dashed lines in FIG. 9 is shown for illustrative purposes only and forms no part of the claimed design.

1 Claim, 8 Drawing Sheets
